Patented Sept. 15, 1914.

UNITED STATES PATENT OFFICE.

ADOLF JACOBY, OF NEW YORK, N.Y.

AEROPLANE.

1,110,792.

Specification of Letters Patent.

Patented Sept. 15, 1914.

Application filed May 26, 1914. Serial No. 841,032.

To all whom it may concern:

Be it known that I, ADOLF JACOBY, a citizen of the German Empire, residing in New York, in the borough of Manhattan, county and State of New York, have invented certain new and useful Improvements in Aeroplanes, of which the following is a specification.

This invention relates to aeroplanes, and has for its object to impart increased stability to the machine while in flight. For this purpose the wings are specially shaped and located so as to give increased resistance against falling.

In the accompanying drawing, Figure 1 is a plan view of an aeroplane embodying the invention. Fig. 2 is a side-view of Fig. 1, and Fig. 3 is a front-view of the machine. Similar reference numerals indicate corresponding parts in all the figures.

Referring to the drawings, and more particularly to Fig. 1, the body 10 of the machine comprises the top 11, side members 12, 13, and inclined bottom members 14, all suitably secured together to give the necessary stability. This body-portion 10 is provided at its rear with a rudder 15, controlled by guiding rods 16 and 17, and at the front of the body 10 is a propeller 18. Planes 20, 21, 22 and 23 are connected with the body 10, and at the rear portion of the body 10 are horizontal rudders 24 and 25, which are mounted on shafts 26 and 27.

The planes 20, 21, 22 and 23 are of a particular and novel shape, in that they are curved from their uppermost point indicated, for instance, by 29, downwardly toward the body 10, and are also curved toward the tip 30 of the plane. They are also curved convexly forward of a straight line between the tips, as seen in Fig. 1. The inner end of each plane is lower than the tip, as seen in Fig. 3. The upper plane is located forward of the lower plane, as seen in Figs. 1 and 2. The curvature of the plane brings about the advantage that the dropping of the aeroplane is impeded, in that by this curving a certain amount of air is gathered by the inclined surfaces of the plane, and underneath the plane. From the extreme forward points 31 of the planes, the planes are curved rearwardly, as indicated by 32, to the tip 30, and from the point 31 to the innermost points 33. A similar curvature exists at the rear edge of the plane, where the curvature commences at the central point

34 and inclines outwardly to the tip 30, and inward to the inner end 36 of the plane. The planes 20, 21, 22 and 23 are provided each with a similar inclination and configuration, and thereby have the advantage of preventing the too rapid falling of the aeroplane. The advantage of curving these planes from the point 31 to the tip as indicated by 32, and of curving from the central point 31 to the inner point 33, as indicated by 37, is that thereby the air, on the forward movement of the planes, may be readily cut, and the aeroplane may readily pass through the air on the forward progressing movement thereof. The tips of the upper planes are on a straight line with the rearmost point of connection of the planes with the body 10, as indicated by dotted line 28, in Fig. 1, and the lower planes have the same horizontal curvature, and are parallel therewith, as shown by the dotted line 39 between the tips of the lower blades.

The rudders 24 and 25 are mounted upon the shafts 26 and 27, which may be oscillated by suitable means within the housing 10, and thereby the planes 24 and 25 are inclined in one or the other direction in respect to the horizontal, and thereby the aeroplane is raised or lowered. The rudder blades 24 and 25 are movable independently of each other, so that the aeroplane may be given any desired inclination. The rudder blades 24 and 25 are provided with a front edge tapered off at its ends, which is clearly indicated at 40, 42, 43, in Fig. 1, and this form of rudder enables very easy entrance and passage of the rudder through the air. The motor and all necessary operating and controlling devices are contained within the body 10.

The propeller blades have their inner portions approximately in line with the tips, as indicated by dotted line 52 in Figs. 1 and 2. The blade has its surface inclined at about 25°, so as to present an inclined plane to the air. This enables a very smooth and rapid movement of the propeller in the air, and the propulsion of the aeroplane by the rotation of the propeller. By my improved planes and propellers, a very improved device is produced.

The three essential features are the location and double curvature or inclination of the planes, the position of the rudders and their shape, and the position of the propeller, and its shape.

The device is usable also in water, and when in water, of course, a boat hull has to be provided in place of the body 10, and the rudder 15 acts as a rudder to the boat.

5 One embodiment of the invention has been shown and described. It is obvious, however, that changes may be made therein without departing from the spirit of the invention as set forth in the claims.

10 I claim:

1. An aeroplane, comprising a body, a vertical rudder at the rear end thereof, a propeller at the forward end thereof, four planes connected with the body portion, said 15 planes being arranged in two pairs, the planes of the upper pair being located forward of and overlapping the planes of the lower pair, one at each side of the machine, each of said planes being convexly upwardly 20 curved, and having its inner end at the connection with the body-portion at a lower elevation than its tip, each of said planes being convexly forwardly curved, and tapered toward its tip, the two tips of opposite planes, 25 and the rearmost point of connection with the body, being located on a straight line, and horizontal rudders, one at each side of the body portion, between the planes and the vertical rudder, each of said horizontal 30 rudders being operable independently of the other.

2. An aeroplane, comprising a body, a

vertical rudder at the rear end thereof, a propeller at the forward end thereof, four planes connected with the body portion, said 35 planes being arranged in two pairs, the planes of the upper pair being located forward of and overlapping the planes of the lower pair, one at each side of the machine, each of said planes being convexly upwardly 40 curved, and having its inner end at the connection with the body-portion at a lower elevation than its tip, each of said planes being convexly forwardly curved, and tapered toward its tip, the two tips of opposite 45 planes, and the rearmost point of connection with the body, being located on a straight line, and horizontal rudders, one at each side of the body portion, between the planes and the vertical rudder, each of said horizontal rudders being operable independently 50 of the other, and the blades of said propeller being straight for approximately one-half their length, and convexly forwardly curved and inclined at approximately 25° 55 for the remainder of their length.

In testimony, that I claim the foregoing as my invention, I have signed my name in presence of two subscribing witnesses.

ADOLF JACOBY.
